UNITED STATES PATENT OFFICE.

ANDREW A. SMITH, OF HOTCHKISS, COLORADO, ASSIGNOR OF ONE-HALF
TO WATSON S. COBORN, OF SAME PLACE.

DESIGN FOR A VEHICLE OR BOX SPRING.

SPECIFICATION forming part of Design No. 24,910, dated November 19, 1895.

Application filed October 1, 1895. Serial No. 564,335. Term of patent 14 years.

To all whom it may concern:

Be it known that I, ANDREW A. SMITH, a citizen of the United States, residing at Hotchkiss, Delta county, Colorado, have invented and produced a new and original Design for Vehicle or Box Springs, of which the following is a specification, reference being had to the accompanying drawing, forming part thereof, and in which the figure is a perspective showing my design.

The leading feature of my design consists in the horizontally-disposed U-shaped spring having its upper and lower parallel members of different lengths and terminating in oppositely-projecting arms, the lower shorter member having an inwardly-extending offset at its free end containing a concavity in its inner face and a corresponding convexity thereunder.

A is the horizontally-disposed U-shaped spring, having its parallel members A' A⁵ of different lengths and terminating in oppositely-projecting arms a⁴ a⁵. The shape of the spring between the legs A' A⁵ is stepped or shouldered, as shown at A² A³, and the leg A⁵ is given a hooked contour between the letters A⁶ a⁵, this hooked portion having a concavity a⁷ and a corresponding convexity a⁸. A band-like figure A⁹ encircles the spring at the bow. 30

What I claim is—

The design for a vehicle or box-spring herein shown and described.

ANDREW A. SMITH.
